R. J. RONEY.

DAMPER REGULATOR FOR HEATERS

APPLICATION FILED APR. 17, 1906

The image contains seven technical drawings labeled Fig. 1 through Fig. 7, illustrating a mechanical device, possibly a hopper or conveyor system. The drawings are as follows:

- Fig. 1:** A side view of a hopper assembly. It features a funnel-shaped hopper body (13) with a vertical support rod (11) and a base (12).
- Fig. 2:** A front view of the hopper assembly. It shows the funnel (13), support rod (11), and a vertical pipe assembly (15, 16, 17) connected to the hopper. A small hopper (4) is shown at the bottom.
- Fig. 3:** A side view of a mechanical assembly. It shows a vertical pipe (42) connected to a circular component (10) with a central rod (8) and a base (9).
- Fig. 4:** A side view of a vertical pipe assembly. It shows a vertical pipe (37) with a flange (34) at the top, connected to a vertical pipe (28) which then splits into two vertical pipes (29, 20).
- Fig. 5:** A side view of a vertical pipe assembly. It shows a vertical pipe (29) connected to a vertical pipe (28) which then splits into two vertical pipes (20, 19).
- Fig. 6:** A side view of a vertical pipe assembly. It shows a vertical pipe (37) with a flange (34) at the top, connected to a vertical pipe (28) which then splits into two vertical pipes (29, 20). A small hopper (4) is shown at the bottom.
- Fig. 7:** A detailed view of a mechanical component. It shows a vertical pipe (35) connected to a circular component (36) with a central rod (30) and a base (27). A small hopper (18) is shown at the bottom.

UNITED STATES PATENT OFFICE.

ROBERT J. RONEY, OF SYRACUSE, NEW YORK.

DAMPER-REGULATOR FOR HEATERS.

No. 893,874.

Specification of Letters Patent.

Patented July 21, 1908.

Application filed April 17, 1906. Serial No. 312,199.

To all whom it may concern:

Be it known that I, ROBERT J. RONEY, of Syracuse, in the county of Onondaga, in the State of New York, have invented new and useful Improvements in Damper-Regulators for Heaters, of which the following, taken in connection with the accompanying drawings, is a full, clear, and exact description.

This invention relates to improvements in damper regulators for furnaces and other heaters which are usually located in the cellar or basement, and are provided with a draft or smoke damper, draft-door and cold-air check-damper or valve, the draft-door and check valve being usually controlled by chains or cables extending to the upper floors of the building, while the main draft or smoke damper is generally adjusted in the cellar only.

20 The essential purpose of my present invention is to enable all three of these dampers to be controlled by a single-operating member in one of the upper rooms of the building, or allowed to return to their normal positions 25 by the operation of a single hand-piece located in the cellar or in proximity to the furnace. By the normal positions of the dampers is meant, that the cold air check-damper is closed, while the smoke-damper and draft-door are open to the maximum degree.

One of the specific objects is to connect the cold-air-check-damper to the draft-door in such manner that when the cold-air check valve or damper is closed the draft door is 35 opened, that is, the cold-air check-damper automatically closes by its own gravity and is of sufficient weight to overbalance the weight of, and to open the draft-door when allowed to close.

40 A further object is to connect the cold-air check-damper and smoke damper with a lost motion sufficient to allow the cold air check-damper to be opened to a limited extent without affecting the position of the smoke-damper, but when moved beyond the limit of its lost motion, operates to close the smoke damper to a greater or less degree, according to the degree of movement of the cold air check-damper. On the other hand, this connection 45 between the cold-air check-damper and smoke damper is such that when the check-damper is allowed to close the smoke damper is positively operated to its full open-position simultaneously with the opening of the draft-door.

Another object is to provide a movable detent for holding the damper-adjusting member in its adjusted position, and to connect said detent to the hand-piece in the cellar whereby it may be tripped to allow the various dampers to return to their normal positions.

A still further object is to conceal the chains or cables extending from the dampers to the adjusting member within the partitions so that those extending to the upper floors of a building cannot be tampered with by persons on the lower floor.

Other objects and uses will be brought out in the following description.

In the drawings—Figure 1 is a vertical sectional view, partly in elevation, of my improved damper-controlling system, as applied to a hot-air furnace which is shown by dotted lines. Fig. 2 is an enlarged vertical sectional view of a portion of the draft-pipe or smoke-pipe and cold-air conduit showing the cold-air check-damper and smoke-damper, and connections between the same. Figs. 3 and 4 are detail sectional views taken 80 respectively on lines 3—3, and 4—4, Fig. 2. Fig. 5 is an elevation, partly broken away, of the damper operating member and detent, together with a part of the supporting-frame or guide. Fig. 6 is a vertical sectional view 85 from front to rear, of the guide or frame for the operating members seen in Fig. 5, showing a concealing tube or case for the chain or cable, which in this instance, is attached to the upper end of the adjusting member. 90 Fig. 7 is a horizontal sectional view taken on line 7—7—, Fig. 6.

In Fig. 1 the furnace, as A—, is represented by dotted lines, and is provided with a rearwardly extending draft-pipe —1— having an upward extension —2— and terminating at its rear end in an upright cold-air check-pipe —3—, the front of the furnace being provided with the usual ash-pit door —4— and main draft-door —5—, which is hinged 95 at its upper edge at —6— to the door-frame —4—. A damper —7— is centrally pivoted and balanced in the pipe —1— between the upright extension —2— and adjacent side of the furnace —A— and is connected at the rear side of its pivot by a link —8— to the adjacent end of a lever —9— which is also centrally pivoted at —10— within the smoke flue —1—. The opposite or rear end of the lever —9— projects into a slot —11— in an 100 105 110

- upright arm —12—, which is secured to the upper end of a conical cold-air check-valve —13—. This valve —13— is movable vertically in the cold-air flue —3— into and out of engagement with a suitable seat —14— just below the adjacent end of the draft-pipe —1— and is preferably hollow and arranged with its apex at the bottom and is open at the top to permit the insertion of additional ballast or weight, as may be desired, to counter-balance the weight of the draft-door —5—. The cold-air pipe —3— is provided with an inlet —3'— some distance below the valve —13— and its seat —14—, which latter are therefore located between the inlet 3'— and the adjacent end of the draft-pipe —1— to cut off communication between the cold-air inlet and draft-pipe when the check-damper is closed.
- 20 One of the objects in tapering the valve 13— downwardly is to enable it to automatically center and adjust itself to its seat 14— when closing, and at the same time, to afford sufficient clearance between the valve and its seat to permit the upward passage of cold air into the draft-pipe when slightly opened for the purpose of reducing the draft through the combustion chamber of the furnace. The upper end of the check-pipe —3— extends some distance above the draft-pipe —1— and is closed by a suitable cap —15— to cut off communication between the draft-pipe and atmosphere, except through the inlet 3'—.
- 35 Secured to the upper end of the valve 13— is a vertical guide-rod or stem 16— which is guided in a cross-bar —17— in the upper end of the pipe —3—, said rod or stem extending upwardly through an aperture in the cap —15— and is connected to one end of a chain or cable —18—, the other end of which is attached to a vertically adjustable operating member 19— located in one of the upper rooms of the building and guided in a suitable wall-plate or frame —20—. The upper end of this rod or stem —16— is also connected to one end of a separate cable —21— which is passed over suitable rollers —22— and has its upper end connected to the free edge of the draft-door —5—, thereby connecting the valve 13— to the draft-door —5—, these connections being so adjusted that when the valve 13— is closed upon its seat —14— the draft-door —5— will be opened to its maximum degree and will be held open by the preponderence of weight of the valve 13—. The chain or cable —18— is passed around suitable rollers —23— so as to exert a direct upward pull on the valve —13—.
- 40 when the adjusting member 19— is moved vertically in its guide —20—. This damper-operating member —19— is provided with a series of teeth —24— on one of its vertical edges adapted to be engaged by a pawl or detent —25— which is pivoted at —26— to the frame —20— and is held in engagement with the teeth by a suitable spring —27—, as best seen in Fig. 5.
- 45 The upper end of the operating member —19— is provided with a hand-piece —28— projecting through a slot —29— in the plate —20—, and it is now evident that by sliding the toothed rack —19— vertically, or upwardly, by means of the hand-piece —28—, the damper or valve —13— will be correspondingly elevated from its seat —14— through the medium of the chain —18—, and that by releasing the toothed rack from the hand, it will be held in its adjusted position by the spring-actuated detent —25—. 70 The valve 13— may therefore, be opened or elevated gradually to any desired degree, during which operation the draft-door 5 closes a corresponding degree by its own gravity, which keeps the chain —21— practically taut so that any movement of the valve 13— causes a similar movement of the draft-door —5—. The damper —7— is practically balanced upon its pivotal bolt, as —7'—, and the lever —9— is also substantially balanced upon the pivotal bolt —10—, so that aside from the positive operation transmitted to the lever —9— and damper —7— by the arm —12—, they would remain in either of their adjusted positions. 80
- 50 The slot —11— in the arm 12— is considerably longer vertically than the adjacent end of the lever —9— which it receives, but these parts —9— and 12— are so relatively adjusted that when the valve 13— is closed upon its seat 14— the upper end of the slot —11— engages and holds the adjacent end of the lever —9— down to the position shown in Figs. 1, and 2, thereby holding the damper —7— in its extreme open position, where it remains during a limited upward movement of the valve 13—, as determined by the length of the slot —11—. This allows the valve 13— and door —5— to be respectively opened and closed a limited distance without effecting any operation of the damper —7—, that is, the cold-air check valve may be opened and the draft-door 5— partially closed without closing the main damper —7—, thereby affording a very close regulation of the draft. 100 If, however, it is desired to close the main draft-damper —7—, it is simply necessary to raise the operating member —19— a trifle higher, thereby further elevating the valve 13— until the lower end of the slot —11— engages and elevates the adjacent end of the lever —9— which depresses the opposite end of said lever and rocks the damper —7— toward, or to the fully closed position, as shown by dotted lines in Fig. 2, or the damper —7— may be adjusted to any intermediate position, depending upon the degree of elevation of the operating member —19—. The connections between the draft-door —5—, valve 13— 110

13—, and damper —7— are so adjusted as to permit the draft-door —5— to nearly close by the elevation of the valve 13— before the lower end of the slot —11— engages 5 the adjacent end of the lever —9— so that the draft-pipe —2— is placed in direct communication with the atmosphere through the inlet 3— and the draft-door —5— is nearly closed before the damper —7— is 10 moved from its extreme open position, but if this does not check the fire sufficiently the damper —7— may be wholly or partially closed by the further upward adjustment of the operating member 19— and valve 13—, 15 thereby completing the closing of the draft-door —5— and the further opening of the valve 13—.

It will be seen from the foregoing description that it is necessary to extend only one 20 of the cables or chains, as —18—, upwardly through the floors of the building to the operating member —19— and that the entire system of draft-regulators —5—, 7— and 13— may be controlled by this one chain 25 because I have provided the detent —25— with an exposed finger-piece —30— which may be depressed by the operator to release the sliding member —19— and allow the latter to fall by gravity assisted by the 30 weight of the valve 13— to its normal position, as seen in Fig. 1, the valve 13— returning to its seat and incidentally opening the valves —5— and —7— through the medium of the chain —21— and lever —9— respectively. 35 It may be desired, however, to trip the pawl —25— from the cellar, and for this purpose I attach to said pawl one end of a chain or cable —31— which is passed downwardly through the floors of the building and 40 around suitable idlers or rollers —32—, and has its other end provided with a handle —33— in proximity to the furnace, and within easy reaching distance of the operator, so that if the regulators are adjusted 45 from their normal position, they may be released by simply pulling down upon the handle —33— to trip the detent —25—.

The main object of the invention is to 50 permit all of the regulators to be controlled from the room in which the adjusting member —19— is located, and in most instances, a single chain will be employed in connection with the operating member —19—, and in order that this chain may be concealed in 55 the partition, it is shown in Fig. 6, as attached to a rearwardly projecting stud —34— on the upper end of the sliding rack —19—, and as inclosed within a suitable case —35— within the partition, that is, behind the lath and plaster, as —36—, said case —35— being inserted through an opening —37— in the wall and is covered by the plate —20—.

In order that the check-pipe —3— and 60 smoke-pipe —2— may be easily removed

and replaced when cleaning the furnace, and also to permit the damper —7— and lever —9— to be readily placed in operation, the draft-pipe —1— is detachable from the check-pipe, and also from the furnace collar, and 70 for this purpose I provide the meeting ends of such parts with suitable collars —38— which are secured by rivets —39— to one of the meeting ends and telescope with the adjacent part, which latter are clamped to the 75 collar by set screws —40—. The pivotal bolts —7— and 10— are journaled in the sides of the draft-pipe —1— and preferably in open-sided slots —41— and —42— in the meeting ends of the collars —38— and draft- 80 pipe section —1— so that when the check-pipe and draft-pipe are separated, the damper —7—, and lever —9— may be removed from the open sided bearing in which they are journaled.

What I claim is:

1. In a device of the character described, a draft-pipe, a damper in the draft-pipe, a check pipe communicating with the draft-pipe, a self-closing valve in the check pipe 90 and connected to the damper with a lost motion, whereby the valve may be opened a limited distance independently of the damper, said connections operating to move the damper when the valve is moved beyond the 95 degree of lost motion, and means for operating the valve.

2. In a device of the character described, a draft-pipe, a check-pipe communicating with the draft pipe, a damper in the draft-pipe, a 100 check-valve in the check-pipe, a lever flexibly connected to the damper and also connected to the valve with a lost motion, whereby the valve may have a limited movement irrespective of the damper, said lever being actuated by the valve when moved beyond the limit of its lost motion to actuate the damper, and means to actuate the valve.

3. In a damper regulator for heaters, the combination of a draft-pipe and a check-pipe 110 projecting downwardly therefrom, the latter being provided with a valve seat below its junction with the draft-pipe, a valve movable vertically and bodily to and from said seat, a damper in the draft-pipe, connections, 115 between the damper and valve whereby the closing of the valve opens the damper, said valve having a limited movement independently of said connections, and means for raising and lowering the valve.

4. In a damper regulator for heaters, a draft-pipe and a check-pipe communicating therewith, a damper in the draft-pipe, a check-valve in the check-pipe, connections between said damper and valve whereby the 125 damper is opened when the valve is closed, said valve being movable a limited distance towards its open position independently of said connections, and means for raising and lowering the valve.

5. In a damper regulator for heaters, a draft-pipe and a check-pipe communicating therewith, a damper in the draft-pipe, a valve in the check-pipe, means actuated by the valve when closing for opening the damper, said valve having a limited movement towards its open position independently of the damper, and means for raising and lowering the valve.
6. In a damper regulator for heaters, a draft-pipe and a check-pipe communicating therewith, a damper in the draft-pipe, a check-valve in the check-pipe, a lever having one end flexibly connected to the damper and its other end connected with a lost motion to the valve, and means for raising and lowering the valve.
7. In a damper regulator for heaters, a

draft pipe and a check pipe communicating therewith, a damper in the draft pipe, a valve 20 in the check pipe, a seat for the valve below the draft pipe, said valve being movable from its seat above the bottom of the adjacent end of the draft pipe, a lever having one end connected to the damper and its other end connected with a lost motion to the valve to permit the latter to be raised a limited distance without effecting the operation of the lever or damper, and means for raising the valve.

In witness whereof I have hereunto set my hand this tenth day of April, 1906.

ROBERT J. RONEY.
